Pennie Davis Marion & Edmunds

UNITED STATES PATENT OFFICE.

FLOYD J. METZGER, OF NEW YORK, N. Y., ASSIGNOR TO AIR REDUCTION COMPANY, INC., A CORPORATION OF NEW YORK.

PRODUCTION OF ALKALI-METAL CYANIDES.

Application filed March 23, 1920. Serial No. 368,101.

To all whom it may concern:

Be it known that I, FLOYD J. METZGER, a citizen of the United States, residing at New York city, in the county of New York, State 5 of New York, have invented certain new and useful Improvements in the Production of Alkali-Metal Cyanides; and I do hereby declare the following to be a full, clear, and exact description of the invention, such as 10 will enable others skilled in the art to which it appertains to make and use the same.

This invention relates to the production of high grade alkali metal cyanides by the fixation of nitrogen and particularly to the 15 recovery of cyanides from furnace products resulting from the heating of mixtures of alkali metal carbonates or oxides and carbon, with or without a catalytic agent such as iron, in the presence of nitrogen or ni- 20 trogenous gases.

Methods of the character described, for example, in United States Letters Patent No. 1,322,195, have been developed to produce a furnace product containing upward 25 to thirty per cent of alkali metal cyanide, the balance consisting of alkali metal carbonate and oxide, carbon and iron, and in U. S. Letters Patent No. 1,385,336, a method of converting the cyanide into hydrocyanic 30 acid is described. The hydrocyanic acid thus released may be liquefied and utilized as such, but the numerous uses of alkali metal cyanides in pure or substantially pure condition suggests the desirability of recombining 35 the acid with an alkali metal.

The object of the present invention is, therefore, to provide a method whereby alkali metal cyanides may be produced in a simple and satisfactory manner from crude 40 furnace products such as are described in the patent above referred to and to permit the utilization of all of the products of the several reactions so that the method is economical and therefore, commercially practicable.

The invention has its foundation in the discovery that the reaction which is depended upon to free the hydrocyanic acid from the furnace product may be reversed 50 under suitable temperature conditions which are readily controlled. Thus, in the converter, the furnace product is treated with carbon dioxide preferably traversing the mass at a rate which precludes the formation 55 of polymers of the acid. The same result

may be accomplished, however, by suitably controlling the temperature of the mass during the contact of carbon dioxide therewith as described in U. S. Letters Patent No. 1,385,335. The hydrocyanic acid is released as such and the residue may be returned to form the basis of mixtures for the cyanide furnace. The hydrocyanic acid may then be caused to react with an alkali metal compound, preferably the carbonate, while 60 the mass is held at a temperature varying from 200° to 500° C. with the result that the alkali metal cyanide is produced in a condition of purity depending on the purity of the alkali metal compound used while carbon dioxide is released, and may be returned for use in the converter to release further quantities of hydrocyanic acid. 70

In the accompanying drawing, I have provided a flow sheet which illustrates the 75 preferred mode of practicing the invention. Referring to the drawing, an alkali metal compound such as the carbonate or oxide is mixed with carbon and a proportion of iron, preferably in the form of an oxide. The 80 proportions may vary but a typical example requires 44 parts of alkali metal carbonate or oxide, 54 parts of carbon such as coke, and two parts of iron in the form of an oxide. The materials are thoroughly commingled in a suitable mixer, being preferably moistened sufficiently to cause the particles to agglomerate. The mass is then dried and is delivered to the furnace where it is subjected to a relatively high temperature, e. g., 950-1100° C., while nitrogen or 85 nitrogenous gases are passed through the furnace in contact with the mass. When the reaction has proceeded to the point which is determined by a study of the conditions of maximum production in a minimum time, the furnace product is discharged to a converter where the mass is moistened and subjected to the action of carbon dioxide. The 95 carbon dioxide is preferably forced through the mass at a comparatively high rate precluding the formation of polymers of hydrocyanic acid. The reaction is indicated as follows:

and hydrocyanic acid is liberated. The residue consisting of alkali metal carbonate and oxide, carbon and iron is returned to furnish the basis of new mixtures until it 110

becomes contaminated with ash from the carbon.

The hydrocyanic acid mixed with the excess of carbon dioxide used, may be condensed and utilized as such but the purpose of the present invention is to produce cyanides and accordingly the mixed gas is delivered to a chamber in which the hydrocyanic acid reacts with an alkali metal compound, preferably a carbonate. The temperature of the chamber is maintained between 200° and 500° C. and at a point which permits the reversal of the reaction previously employed to free the acid. The result is an alkali metal cyanide, and carbon dioxide which is returned for use in the converter to release more hydrocyanide acid.

From the foregoing it will be apparent that the method described has the advantages of simplicity and economy. All of the materials are handled in a dry condition and there are no by-products except the waste gases from the cyanide furnace and that portion of the residue which eventually becomes contaminated with ash. Aside from replacements of alkali metal compound and iron thus required, the only materials required are carbon, nitrogen and the alkali metal compound which forms the final basis of the cyanide. Carbon dioxide is generated in substantially sufficient quantity to supply the converter and any additional supply required may be drawn from a suitable source. A product of considerable value is made

from relatively cheap materials, the principal cost factors being the heat and labor required in carrying out the method.

Various changes may be made in the details of the method and the proportioning of the material employed without departing from the invention or sacrificing any of its advantages.

I claim:

1. A method of recovering alkali metal cyanide from crude furnace products, which comprises subjecting the solid furnace product to the action of carbon dioxide under conditions precluding the polymerization of the hydrocyanic acid released, and subsequently combining the hydrocyanic acid with a solid alkali metal compound while the compound is maintained at a temperature between 200° and 500° C.

2. A method of recovering alkali metal cyanide from crude furnace products, which comprises subjecting the solid furnace product to the action of carbon dioxide under conditions precluding the polymerization of the hydrocyanic acid released, subsequently combining the hydrocyanic acid with a solid alkali metal carbonate while the carbonate is maintained at a temperature between 200° and 500° C., and returning the carbon dioxide released to decompose further quantities of the furnace product.

In testimony whereof I affix my signature.

FLOYD J. METZGER.
